CHURN

Albert C. Hougland, St. Paul, Minn., assignor to
 Crane Company of Minnesota, St. Paul, Minn.,
 a corporation of Minnesota

Application April 16, 1936, Serial No. 74,703

7 Claims. (Cl. 31—33)

It is an object of this invention to provide a novel and relatively inexpensive churn and butter worker of the commercial type having a cylindrical churn body in which all of the butter making and working elements are fixed or stationary.

Another object is to provide a churn with novel butter working members comprising shelves so formed and associated with the cylindrical churn walls that an elongated mass of the butter is caused to be twisted about its longitudinal axis, alternately in opposite directions during the working operation.

A particular object is to provide a churn with one or more butter working shelves each composed of a plurality of plane members extending from end to end of the churn and tapering in width longitudinally of the churn body.

My improved churn has the advantages of improved sanitation, lower cost and efficient working of the butter resulting from the elimination of all rotating parts in the butter chamber and is also simpler and less expensive to manufacture than other churns having fixed butter working elements known to me.

Referring to the accompanying drawings which illustrate the best form of my invention at present known to me:

Figure 1 is a horizontal section through the axis of the cylindrical churn body and showing the butter working shelves in plan view;

Fig. 2 is a vertical section through the axis of the churn;

Fig. 3 is a vertical section taken transversely through the axis of the churn on the line 3—3 of Fig. 2, and

Fig. 4 is a perspective view showing the two principal members or planks comprising one of the shelves.

I provide a cylindrical churn body 5 of suitable size and proportions for commercial use. This body has end walls 6 and 7 and is preferably constructed of wood with the usual or suitable external metal reinforcement (not shown). To support the churn body for rotation about its axis and with its axis disposed horizontally, I provide standards 8 and 9 formed with bearings for axial shafts 10 and 11 respectively projecting from the end walls 6 and 7. Suitable spiders 12 are formed integral with the shafts 10 and 11 and are secured to the end walls 6 and 7. The standards 8 and 9 are connected together by longitudinal frame members 13 and power for rotating the churn body is transmitted from a pulley 14 through suitable gearing in a housing 15 to the

shaft 11. The gearing is of the change speed type and includes gears 16 and 17 slidably mounted on a shaft 18, and gears 19 and 20 fixed on the shaft 11. A manually operable lever 21 is provided to shift the gears 16 and 17 along the shaft 18 for changing from the higher speed desirable for churning to the lower speed required for working the butter.

Mounted within the churn body 5 and extending from end to end thereof are two, oppositely disposed, shelves indicated generally by the numerals 22 and 23 respectively. As best shown in Figs. 3 and 4, the shelf 22 is composed of plane wooden members 24 and 25 angularly disposed to each other and with their adjoining edges 26 and 27 extending longitudinally in parallel, straight lines which are oblique to the axis of the churn. These edges are slightly spaced apart to facilitate cleaning and the outer edge 28 of the member 24 extends in parallel, slightly spaced relation to the elements of the cylindrical body 5, that is, in parallel relation to the axis of the churn body. The working face of the member 24 extends obliquely to the radii of the churn intersecting this surface, that is, in a plane which, when extended, is tangent to an imaginary cylinder having a common axis with the cylindrical body 5. As clearly shown in Fig. 3, the working or upper face of the shelf member 25 is not tangent to such imaginary cylinder, but extends in a plane which is oblique to the axis of the churn body.

The several shelf members are considerably wider at one end than at the other, and the member 24 has its wide end abutting against the end wall 6 of the churn body and its narrow end abutting against the wall 7. The reverse is true of the member 25 which has its narrow end against the wall 6 and its wide end against the wall 7 of the churn. The shelf 23 comprises members 29 and 30, similar respectively to the members 24 and 25, except that the small end of the member 29 and the large end of the member 30 abut against the wall 6 of the churn body. As the shelf 24 is diametrically opposite the shelf 23, it will be apparent that the working face of the member 30 extends in a plane which is parallel to the working face of the member 25 and the working face of the member 29 is parallel to the face of the member 24. The shelf members are secured to the cylindrical body of the churn by suitable brackets 31 located in a vertical plane about midway between the walls 6 and 7 and the ends of the shelves are secured to the walls 6 and 7 of the churn body by suitable means, such as brackets 32.

Extending along the axis of the churn body is a bar 33 adapted to coact with the inner edges of the members 25 and 30 in retarding an end of the mass of butter on the shelves successively during the working operation, as more fully described hereinafter. The bar 33 is secured broadside to the inner edges of the shelves by bolts 34 accessible through the shafts 10 and 11, as indicated in Figs. 1 and 2. Adjoining and extending along the working face of the shelf 22 is a pair of doors 35 of the usual or suitable construction to allow access to the interior of the churn.

Operation

15 During the churning the body 5 is rotated about its axis, in the direction indicated by an arrow in Fig. 3, by power transmitted from the pulley 14 through shaft 18, gears 16 and 19 and shaft 11. The cream is agitated by the shelves 20 22 and 23 and because of the oblique or longitudinally inclined positions of the members 25 and 30, is caused to surge alternately to and from the end walls 6 and 7. Rapid and thorough churning results. Upon completion of the churning, the buttermilk is withdrawn and the desired amount of water and salt, when the latter is required, for the working are added to the butter in the churn body. The doors 35 are then closed and the churn rotated at the lower rate through 30 the gears 17 and 20. During the working, the butter is retained in a single, unitary and elongated mass extending from end to end of the churn body. The direction of rotation being as indicated in Fig. 3, this elongated mass is picked 35 up and then rolled from first one shelf and then the other. Thus, the mass is lifted on the shelf 22 as this shelf is raised at the left of the cylindrical body, as seen in Fig. 3, its lateral inclination increases until the narrow, lower end of 40 the member 25 allows the corresponding end of the butter mass to roll off the shelf. This twists the mass, part of which is retained on the rising shelf by the wider portions of the member 25. The bar 33 assists in the twisting action by coacting 45 with the wide end of the member 25 to retain the mass of butter on the shelf at one end of the churn body while the other end of the mass rolls off. This twisting progresses from end to end of the mass of butter which normally retains its 50 unitary form. As the rotation continues the entire mass of butter finally falls from the shelf 22 and is immediately picked up by the shelf 23. The latter repeats the operation just described but twists and rolls the mass in the reverse direction because of the fact that the wide end of the shelf member 30 is located opposite the narrow end of the shelf member 25 and causes the end of 55 the mass of butter which first left the shelf 22 to leave the shelf 23 last. This alternate twisting 60 and rolling of the mass of butter in the water and salt, without breaking up the mass into a multiplicity of small bodies, results in a uniform, thorough and rapid working of the butter fat, salt and water together and produces the desired waxy and 65 uniform consistency.

It will be evident that the manufacture of the butter working shelves and the mounting of the same within the churn body is a relatively simple operation because the several shelf members all 70 have the straight, plane form. These members are preferably constructed from wood stock about two inches in thickness and the members for each shelf may be obtained by merely cutting a plane and suitably wide plank obliquely or diagonally to form the edges 26 and 27, as indicated

in Fig. 4. The mounting of the shelf within the churn body is also facilitated by the fact that the outer edges of the shelves extend in parallel relation to the axis of the churn body. Another advantage obtained by my improved arrangement 5 of butter working shelves results from the location of one shelf so that it extends continuously, just beneath the doors 35. This facilitates the unloading of the finished butter from the churn because the mass is positioned on the shelf 22 10 where it is readily accessible for removal through both doors.

I prefer to construct each shelf from a plurality of plane members, but it will be evident that a similar shelf may be constructed from a single 15 piece of material within the spirit of my invention. The working face of a shelf may be given the equivalent concavity or dish-shape after suitable steaming of a unitary piece of wooden stock, or like forms may be constructed from stainless 20 metal.

Having described my invention, what I claim as new and desire to protect by Letters Patent is:

1. A churn comprising a cylindrical body disposed with its axis horizontal and arranged to be rotated about its axis and a fixed butter working shelf extending from end to end of said body along the inner periphery thereof, said shelf having its outer edge extending substantially parallel to the axis of said body and having an inner edge portion adapted to support a mass of butter in said body and sloping from one end of said body toward the other end, obliquely to the axis of said body.

2. A churn comprising a cylindrical body disposed with its axis substantially horizontal and arranged to be rotated about its axis and fixed butter working shelves extending from end to end of said body along and adjacent to diametrically opposite inner peripheries thereof, each of said shelves having its outer edge extending substantially parallel to the axis of said body and an inner edge portion adapted to support a mass of butter in said body and sloping from one end of said body toward the other end, obliquely to the axis of said body, said shelves being arranged to twist said mass of butter alternately in opposite directions about the longitudinal axis of said mass.

3. A churn comprising a cylindrical body disposed with its axis horizontal and arranged to be rotated about its axis and a single pair of fixed butter working shelves, each extending from end to end of said body adjacent to the inner periphery thereof, each shelf having its outer edge disposed substantially parallel to the axis of said body and each having an inner edge portion extending obliquely to the axis of said body, one of said shelves being diametrically opposite the other in said body and said inner edge portions of said shelves being substantially parallel to each other.

4. A churn comprising a cylindrical body disposed with its axis horizontal and arranged to be rotated about its axis, a fixed butter working shelf extending along the interior of the cylindrical wall of said body from end to end thereof, said shelf comprising a member having its outer edge extending substantially parallel to the axis of said body and its inner edge extending obliquely to said axis, and a second member extending 65 along the inner edge of said first mentioned member, said second member being wider at one end than at the other, and means for rotating said body whereby butter, during the working operation, is carried upward on said shelf and is caused 70 75

to roll therefrom starting at one end of the churn body and progressing to the other end.

5. A churn comprising a cylindrical body disposed with its axis horizontal and arranged to be rotated about its axis and a fixed butter working shelf extending along the interior of the cylindrical wall of said body from end to end thereof, said shelf comprising, a plane member having its outer edge extending substantially parallel to the 10 axis of said body and its inner edge extending obliquely to said axis, and a second plane member extending along the inner edge of said first mentioned member in a plane angularly disposed to the plane of said first mentioned member, said 15 second member being substantially wider at one end than at the other.

6. A churn comprising a cylindrical body disposed with its axis substantially horizontal and arranged to be rotated about its axis and a fixed 20 butter working shelf extending along the interior of the cylindrical wall of said body from end to end thereof, said shelf comprising, a plane member having its outer edge extending substantially parallel to the axis of said body and its inner 25 edge extending obliquely to said axis, the working

face of said member defining a plane which is tangential to an imaginary cylinder coaxial with said body, and a second plane member extending along the inner edge of said first mentioned member, said second member being wider at one end 5 than at the other and the working face of said second member defining a plane oblique to the working face of said first mentioned member.

7. A churn comprising a cylindrical body disposed with its axis horizontal and arranged to be 10 rotated about its axis, a fixed butter working shelf extending from end to end of said body along the inner periphery thereof, said shelf having its outer edge extending substantially parallel to the axis of said body and having an inner edge portion sloping continuously from one end to the other of said body, obliquely to the axis of said body, and a bar extending along the inner edge of said shelf and so spaced from said shelf as to 15 coat with the inner edge thereof in retarding a 20 mass of butter on said shelf and permitting the mass of butter to fall progressively from end to end between said bar and shelf.
